UNITED STATES PATENT OFFICE

FREDERICK M. VENZIE, OF PHILADELPHIA, PENNSYLVANIA

BUILDING STRUCTURE

Application filed December 17, 1928. Serial No. 226,453.

This invention, generally stated, relates to a building structure and has more especial relation to means for supporting cementitious slabs as used in ceiling and wall constructions.

The leading object of the present invention may be said to reside in the provision of means whereby unskilled labor may more rapidly and efficiently erect ceiling and wall 10 slabs of cementitious material, thereby to reduce building costs.

A further object of the present invention is to provide a structure of the character stated which not only is entirely constructed of fire 15 proofing material but is sound proof, very strong, and very cheap to erect.

A still further object of the present invention is to provide various forms of metallic 20 clips for supporting adjacent ends of the cementitious slabs, said clips being provided with rounded corners to prevent fracture of the slabs in assembly.

A still further object of the present invention is to provide means for tying together 25 adjacent slabs of cementitious material.

Other and further objects of the present invention reside in the provision of the general arrangement, combination, and construction of parts for attaining the results sought 30 by the foregoing objects.

The invention consists of the novel construction hereinafter described and finally claimed.

The nature, characteristic features and 35 scope of the invention will be more fully understood from the following description taken in connection with the accompanying drawings forming part hereof, and in which:

Fig. 1, is a view partly in section illustrating a ceiling and wall structure embodying the invention.

Fig. 2, is a view of the underside of the ceiling slabs shown in Fig. 1.

Fig. 3, is a fragmentary view in elevation illustrating certain of the parts shown in Fig. 1.

Fig. 4, is a fragmentary view in elevation illustrating the manner of using the clips 50 shown in Fig. 5.

Fig. 5, is a view in perspective illustrating the clip shown in Fig. 4.

Fig. 6, is a view in perspective of another type of clip.

Fig. 7, is a view in perspective of the clip 55 shown at the lower portion of Fig. 1.

Fig. 8, is a view in perspective of one of the tie wires shown in Figs. 1 and 2.

For the purpose of illustrating my invention I have shown in the accompanying 60 drawings one form thereof which is at present preferred by me, since the same has been found in practice to give satisfactory and reliable results, although it is to be understood that the various instrumentalities of which 65 my invention consists can be variously arranged and organized and that my invention is not limited to the precise arrangement and organization of the instrumentalities as herein shown and described. 70

Referring to the drawings in detail, the reference numeral 1 designates the wall of a building. The reference numeral 2 designates a vertically disposed beam spaced apart from the wall 1, as clearly shown in Fig. 1, 75 to provide an air space 3. 4 designates a horizontally arranged beam supported at its ends by the wall 1. The beam 4 is also supported by means of straps 5 supported from cross beams 6, which latter in turn are supported by hangers 7. The reference numeral 8 designates ceiling slabs which abut against the underside of the beams 4. These slabs 8 are supported from the beams 4 by means of 80 clips, best seen in Fig. 6. These clips comprise vertically arranged arms 9 provided at their tops with horizontally extended wings 10, and at their bottoms with horizontally extended wings 11, and intermediate 85 of the wings 10 and 11 with other horizontal wings 12. The wings 10 which rest upon the tops of the beams 4 are cut away as at 13 so that the cut-away portion 13 may be snapped over the top of the beams 4 to effect a relatively tight joint. The centrally arranged or intermediate wings 12, which are 90 arranged in opposed pairs, serve to provide jaws to accept the slabs 8. The ends of the wings 12 are rounded as at 14 so that fracture 95 of the slabs 8 which usually are covered with 100

asbestos paper will not occur during an inserting period. It may be stated at this time that the ceiling slabs 8 are first erected and thereafter the wall slabs 15 are erected.

Adjacent the end walls of the building, 5 clips are provided to support those ends of the ceiling slabs adjacent the wall slabs. Such a clip is shown in Fig. 7 and comprises a flat, horizontal portion 16 and a vertical portion 17. The part 16 is provided with 10 slots 18 which may be alternately caused to engage around a beam 2. This is so that if a beam 2 is reversed in position the clip may still be positioned thereon. The part 15 of the clip as shown at the upper left hand side of Fig. 1 engages a beam 2 and the part 17 engages below and supports the inner end of a slab 8. At the bottom of Fig. 1 the same type of clip is employed, but 20 in this case the part 16 is flush with the floor 19 and the clip is secured thereto by means of a nail 20 and the part 17 is nailed as at 21 to a wall slab 15. In the connection it may be remarked that the free end of the 25 part 17 is curved as at 22 in order to prevent fracture of slabs 15, which like slabs 8 are covered with asbestos paper, when fitted to place. Adjacent slabs 15 have fitted therebetween a clip as seen in Fig. 5. This clip 30 comprises a horizontally arranged member 23 which has vertically extended therefrom a series of opposed fingers 24 and a series of opposed depending fingers 25. Both the fingers 24 and the fingers 25 at their free ends are outwardly curved as at 26 in order 35 to prevent fracture of slabs when the same are being positioned with respect to the clips. Reference to Fig. 4 will disclose the clips shown in Fig. 5 properly positioned with respect to the slabs 15. Each slab 15 is apertured as at 27, see Fig. 1. Arranged for passage through these apertures 27 is the tie wire shown in Fig. 8. This tie wire comprises a member 28 which is free to move with respect to the prongs 29 so that when the 40 member 28 is moved to parallelism with the prongs 29 it may be inserted through the apertures 27 and the member 28 permitted to assume a vertical position, as is shown in Fig. 1, whereupon the prongs 29 may be drawn outwardly and twisted as at 30 with respect to an adjacent device, thereby securely holding the slabs in place.

Having placed the ceiling and wall slabs 45 in position, plaster 31 is added which is shown at the right hand side of Fig. 1 in full lines and by dashed lines at the left hand side of Fig. 1. It is preferable to reinforce the plaster as at 32 and in the connection it may be remarked that the reinforce 50 can be conveniently attached to the clips shown in Fig. 6 by means of wire 33. Each of the clips may be stamped from a single piece of metal and the clips shown in Figs. 6 and 7 may each be apertured as at 34 so

that nails may be driven therethrough for engagement with the slabs. Additional clips may be employed as shown in Fig. 3 at certain points for supporting the slabs 15. These clips are provided with vertically disposed lips 35 which are upwardly extended and downwardly extended lips 36. These lips may also be apertured as at 34 for nail reception.

I am aware that the invention may be 70 embodied in other specific forms without departing from the spirit or essential attributes thereof, and I therefore desire the present embodiment to be considered in all respects as illustrative and not restrictive, 75 reference being had to the appended claims 80 rather than to the foregoing description to indicate the scope of the invention.

What I claim is:

1. In a building structure, ceiling and 85 wall slabs of cementitious material, said slabs being apertured, tie wires each comprising a unitary structure extended through said apertures, unitary structures of adjacent slabs being secured together, clips having 90 U-shaped jaws for engaging adjacent ends of said slabs, and a coating of plaster for covering the exposed faces of said slabs.

2. In a building structure, horizontal and 95 vertical I-beams, ceiling and wall slabs of cementitious material, said slabs being apertured, tie wires each comprising a unitary structure extended through said apertures, unitary structures of adjacent slabs being secured together, clips having U-shaped jaws 100 for engaging adjacent ends of said slabs, for securing said slabs together and to said I-beams, and a coating of plaster for covering the exposed faces of said slabs.

3. In a building structure, horizontal and 105 vertical I-beams, ceiling and wall slabs of cementitious material, said slabs being apertured, tie wires each comprising a unitary structure extended through said apertures, unitary structures of adjacent slabs being 110 secured together, clips having U-shaped jaws for engaging adjacent ends of said slabs for securing said slabs together and to said I-beams, said clips being formed of spring metal and having cut away portions for 115 engaging said I-beams, and a coating of plaster for covering the exposed faces of said slabs.

4. In a building structure, ceiling and wall 120 plaster boards of cementitious material, said plaster boards being apertured entirely therethrough, a tie piece extended through an aperture of each plaster board, each tie piece 125 consisting of spaced wires twisted together at their forward ends to form a loop having a cross-bar arranged in swiveled relation with said loop, said cross-bar straddling said aperture at the rear of the plaster board, the free ends of said spaced wires having twisted relation with the free ends of the spaced wires 130

of a tie piece of an adjacent plaster board to couple together the forward faces only of the plaster boards, clips having U-shaped jaws for engaging adjacent ends of said plaster boards, and a coating of plaster for covering the exposed faces of said plaster boards.

5. In a building structure, horizontal and vertical I-beams, ceiling and wall slabs of cementitious material, said slabs being apertured entirely therethrough, double end tie wires having swiveled cross-bars extended through said apertures, adjacent tie wires being secured together, clips having U-shaped jaws for engaging adjacent ends of said slabs, 10 for securing said slabs together and to said I-beams, and a coating of plaster for covering the exposed faces of said slabs.

6. In a building structure, horizontal and vertical I-beams, ceiling and wall slabs of cementitious material, said slabs being apertured entirely therethrough, a double ended tie wire having a swiveled cross-bar extended through an aperture of each slab, tie wires of adjacent slabs being secured together, clips 25 having U-shaped jaws for engaging adjacent ends of said slabs for securing said slabs together and to said I-beams, said clips being formed of spring metal and having cut away portions for engaging said I-beams, and a 30 coating of plaster for covering the exposed faces of said slabs.

7. In a building structure, conventional ceiling and wall plaster boards, the ceiling boards being vertically apertured entirely 35 therethrough and the wall boards being horizontally apertured entirely therethrough, a tie piece extended through an aperture of each plaster board, each tie piece consisting of spaced wires twisted together at their forward ends to form a loop having a cross-bar arranged in swiveled relation with said loop, 40 said cross-bar straddling said aperture at the rear of the plaster board, the free ends of said spaced wires having twisted relation with the free ends of the spaced wires of a tie piece 45 of an adjacent plaster board to couple together the forward faces only of the plaster boards, clips having U-shaped jaws for engaging adjacent ends of said plaster boards, and flat horizontal portions for said clips which horizontal portions are notched to engage an I-beam.

8. In a building structure, conventional 55 ceiling and wall plaster boards, the ceiling boards being vertically apertured entirely therethrough, and the wall boards being horizontally apertured entirely therethrough, tie wires extended through said apertures, said 60 tie wires including parallel wires twisted at one end to form a loop, a cross piece having swivelled relation with said loop, and arranged to straddle the aperture of a plaster board at a plaster board rear.

65 9. In a building structure, conventional

ceiling and wall plaster boards, the ceiling boards being vertically apertured entirely therethrough, and the wall boards being horizontally apertured entirely therethrough, a tie piece extended through an aperture of each plaster board, each tie piece consisting of spaced wires twisted together at their forward ends to form a loop having a cross-bar arranged in swiveled relation with said loop, 70 said cross-bar straddling said aperture at the rear of the plaster board, the free ends of said spaced wires having twisted relation with the free ends of the spaced wires of a tie piece of an adjacent plaster board to couple together the forward faces only of the plaster boards, 75 clips having U-shaped jaws for engaging adjacent ends of said plaster boards, and flat horizontal portions for said clips which horizontal portions are notched to engage an I-beam, 80 said clips having horizontal parts and a series of vertically disposed up-turned, down-turned fingers, the free ends of said fingers being slightly rounded.
